CLAIM

The ornamental design for a vehicle treatment system as shown and described.

DESCRIPTION

FIG. 1 is a front-side bottom perspective view of a vehicle treatment system;

FIG. 2 is a rear-side top perspective view of the vehicle treatment system of FIG. 1;

FIG. 3 is a front view of the vehicle treatment system of FIG. 1;

FIG. 4 is a rear view of the vehicle treatment system of FIG. 1;

FIG. 5 is a left side view of the vehicle treatment system of FIG. 1;

FIG. 6 is a right side of the vehicle treatment system of FIG. 1;

FIG. 7 is a top view of the vehicle treatment system of FIG. 1;

FIG. 8 is a bottom view of the vehicle treatment system of FIG. 1; and,

FIG. 9 is a front view of the vehicle treatment system of FIG. 1, shown in an environment of use.

The broken lines in the drawings illustrate portions of the vehicle treatment system that form no part of the claimed design.

1 Claim, 7 Drawing Sheets
